UNITED STATES PATENT OFFICE.

JOHN A. SALL, OF ROCKFORD, ILLINOIS.

VEHICLE HEATER.

Application filed December 8, 1923. Serial No. 679,461.

This invention relates to heating apparatus for motor vehicles for heating the occupant's compartment, and to a radiating heater which utilizes as the heating medium the exhaust gases from the motor.

The primary object of my invention is to provide an improved heater adapted to be set into an opening in the floor of a motor car or the like, and having a floor plate provided with circulation openings, and a heat radiating element supported below the floor plate and adapted to be supplied with exhaust gases by means of a suitable connection with the exhaust line of the motor, so that heat from such gases ordinarily wasted, is utilized for heating the interior of the car by radiation. I have also aimed to provide improved means for admitting air to the heater for improving the circulation of the radiated heat and for ventilating the inclosure being heated.

Another object is to provide a simplified heater of the character described, composed of but comparatively few parts, constructed and arranged in such novel manner as to enable production thereof at a relatively low cost. In the present embodiment, practically all of the parts are castings, and the only machining required is for drilling and tapping a few screw holes. Some of the parts may however, be formed of sheet metal stampings, as will be presently apparent.

I have further aimed to provide a heater constructed with the foregoing in view, which may be readily installed in the floor of practically any motor vehicle. To facilitate installation, the inlet and outlet gas fittings may be quickly adjusted without disassembling, to suit the particular location of the inlet and outlet connections on the car.

Other objects and attendant advantages will be appreciated by those skilled in this art as the invention becomes better understood by reference to the following description when considered in connection with the accompanying drawings, in which—

Figure 1 is a top view of a heater embodying my invention, with part of the top plate and heater element broken away to show the construction below;

Fig. 2 is a front elevation of the heater; Figs. 3 and 4 are enlarged cross-sectional views taken substantially on the lines 3—3 and 4—4, respectively, of Figs. 2 and 1;

Fig. 5 is a plan view of one of the coupling collars;

Fig. 6 is a section through the collar taken on the line 6—6 of Fig. 5;

Figs. 7, 8 and 9 are front, side and top views respectively, of one of the cams for opening and closing a ventilation door or damper; and

Fig. 10 is a top view of the main housing or casing.

While the improvements disclosed herein are adapted for application in a heater employing different heating mediums and used for heating any inclosure, the present embodiment is particularly designed to be mounted in the floor board of a motor-driven vehicle. Inasmuch as the present invention relates to the heater per se, the intake and exhaust connections other than the exterior fittings directly attached to the heater are not shown in the drawings, as it is obvious that they may be of any suitable or preferred construction.

The heating element is supported in a housing or casing composed preferably of a floor plate and a bottom housing designated generally by 11 and 12, respectively. The floor plate preferably elongated and rectangular in form, has circulation openings 13 throughout its major area and has a marginal flange 14 about said openings adapted to overlie the floor board 15 and to be secured thereto by screws passing through openings 16 at the corners. In the present embodiment, the top plate which is cast preferably of aluminum, has formed on the underside of its marginal portion 14, a recess or locating seat 17 for the reception of the top flange 18 on the housing 12. As shown in Fig. 4, a heat insulating packing 19, preferably of asbestos, is interposed between the flange 18 and the floor board 15. It will be observed that the underside of the marginal portion 14 of the floor plate 11 does not reach to the bottom of the flange 18, consequently the fastening screws or bolts located in the holes 16 clamp the flange 18 between the floor plate and packing 19 and to the floor board, thus rigidly securing the housing 12 in position. The

housing 12 supports a heating element, and has formed in its bottom 21 at opposite ends thereof, openings 22 and 23 for the inlet and outlet of the exhaust gases which furnish the heating medium for said element.

The housing has also formed in its bottom intermediate said openings, one or more, two at present, ventilation or damper openings 24 and 25. While the housing 12 is shown in the form of a casting, this part may be of sheet metal of sufficient gage and shape to insure the necessary strength and rigidity.

The heating element of the radiator type, designated generally by 26, is preferably 10 cast in one piece. It comprises two radiator pipes 27, the ends of which are joined by heads 28 seated on the bottom of the housing, each head having an opening 29 registering with the adjacent inlet or outlet 15 opening as the case may be, in the housing. A packing gasket 31 interposed between the heater and bottom 21 provides an effective seal and heat insulation between parts. The heater is rigidly secured at each end 20 to the bottom 21 by bolts 32, which are also utilized for connecting the inlet and outlet fittings to said bottom as will be presently described. This one-piece heater gives a large radiating area, and because of its construction may be produced at a low cost. 25 It will be observed that the heater pipes 27 span the damper openings 25 lengthwise, and that these pipes are of comparatively large diameter and present a large radiating 30 surface well adapted for heating a comparatively large volume of fresh air taken in through the damper openings, and are likewise adapted for radiating more intense heat when the damper openings are closed, 35 as will be presently described. As shown in Fig. 3, each pipe 27 has cast on its upper side, intermediate its ends, a lug 33 which is practically touches the floor plate and is adapted to give support thereto when heavy 40 weight is brought to bear thereon.

The exterior fittings for the inlet and outlet openings being alike, a description of one will suffice. Each comprises an elbow conduit 34, one end of which has an annular 45 flange 35 adapted to be supported against the underside of the housing bottom 21 in registration with its respective inlet or outlet opening. A coupling collar 36 attached to said bottom by the above-mentioned bolts 50 32, holds the elbow in position. This collar has a seat 37 for the reception of the elbow flange 35 and diametrically opposed openings 38 for the bolts 32. A packing gasket 39 interposed between the bottom 21 and 55 the coupling and elbow parts has an upturned annular flange 41 which covers the wall of the opening 22 and serves as an additional heat insulation between the housing 12 and the heating medium. Viewing 60 Fig. 4, it will be observed that the bolts 32 pass through both the coupling collar and the bottom 21 and are threaded into the heater casting. Upon tightening these bolts 65 the heater and elbow will be fixedly secured to the housing, and upon loosening the

bolts the elbow will be freed so that it may be rotatably adjusted on the seat 37 for the purpose of turning its depending end in any direction. This simple and easy adjustment of the elbow 34 without disassembling 70 or removing any of the parts permits of quick and easy installation of the heater, for the reason that the elbows may be turned to accommodate the inlet and outlet gas connections, and then be rigidly secured 75 in position by tightening the bolts. The packing gaskets 31 and 39 insure a tight joint between the connected parts and serve to heat insulate the bottom 21 from the elbows and heater element. 80

One of the advantages of the foregoing construction is that it is not necessary to machine any of the parts secured together by the bolts 32 other than to drill and tap the bolt holes. This makes for economy in 85 cost of production for the reason that the connected parts may all be castings with the exception of the housing, which may if desired, be in the form of a stamping.

The circulation or damper openings 24 and 25 are adapted to be opened and closed by doors or dampers 42 and 43, respectively, each having hinge plates 44 cast integral therewith. The hinge plates of both doors 90 are concentrically mounted on pintles 45 intermediate the doors, so that the latter open downwardly, one at the front and the other at the back of the heater. Suitable springs 46 on the pintle urge the doors to a 95 closed position. 100

An individual damper control is provided for opening and closing each damper door, and holding it in any intermediate position. The controls for the doors 24 and 25, 105 operated by small hand levers 47 and 48 on top of the floor plate 11, being identical, a description of one will apply to both. The handle 47 is fixed to the upper end of a shaft 49 journaled at 51 in the floor plate, and at 52 in the housing. The shaft projects below the housing and is equipped on its lower end with a cam carrier 53 fixed to the shaft by a set screw 54, and with a compression spring 55 which holds the hub of 110 the hand lever 47 down on the floor plate, thus preventing vibration of the shaft and tending to hold it in any adjusted position. The housing is recessed at 56 for the reception of the spring, in order to locate the shaft as shown. The cam carrier has an 115 arcuate inclined cam portion 57 located between a bearing surface 58 on the underside of the housing and a projecting lug 59 on the door 42, so that by turning the handle 120 in a clockwise direction, viewing Fig. 1, the cam will open the door. A stop 61 on the cam carrier limits rotation thereof in a closing direction by contact with the lug 59; 125 and a depression 62 in the opposite end of 130

the cam is adapted to receive said lug and thereby hold the cam with the door in the full-open position. It will be observed that in the foregoing construction, the single set 5 screw 54 serves to hold the shaft 49, cam carrier, the floor plate and housing in operative relation.

From the foregoing, it will be manifest that a greater or lesser amount of air may be admitted through the damper openings 10 24-25 by operation of the control levers 47-48, thus not only providing for ventilation but also varying the degree of heat delivered into the car. The damper doors are 15 also intended to permit air to be exhausted from the interior of the car as well as supplied thereto; and I have found that the particular function of the doors in this regard varies in different cars. That is, 20 whether the opening of door 42 or 43 induces an inlet or exhaust current depends on the structural makeup of the under body and adjacent parts of the car, which obviously influence air currents beneath the car when 25 it is in motion. Thus, with the construction herein disclosed, that is, with the front and back damper doors, either an inlet or an exhaust current of air may be induced, according 30 to the temperature or to the ventilation condition desired.

From the foregoing, it will be observed that my improved heater is composed of comparatively few parts, and that these 35 parts are so constructed that they may be produced at a low cost. It should be understood, however, that changes may be made in details of construction without departing from the spirit and scope of the invention 40 as expressed in the appended claims.

I claim:

1. A car heater of the character described comprising a heater-supporting casing having two independently regulable damper doors, one at the front opening forwardly and the other at the rear opening rearwardly. 45

2. In a car heater of the character described, the combination of a heater-supporting casing adapted to be set in the floor, a radiating heater in the casing, and a plurality of damper doors on the casing, one opening forwardly and another opening rearwardly. 50

3. In a car heater of the character described, the combination of a heater casing adapted to be set into and projecting below a floor and having air circulation openings in its top and bottom, a radiating heater in said casing, and a pair of damper doors on the bottom of the casing, one opening downwardly toward the front of the car and the other opening downwardly toward the back. 55

4. A heater of the character described comprising a heater casing composed of a

floor plate having air circulation openings, a bottom housing having spaced inlet and outlet openings and an interposed damper opening, a radiating heater in said housing having inlet and outlet ends registering with said inlet and outlet openings and a radiating portion spanning said damper opening, exterior fittings for said inlet and outlet openings each comprising an elbow having an annular flange, a coupling collar having a retaining seat for said flange, and means 65 for securing said collar to the bottom of the housing and permitting the collar to be loosened so that its elbow may be turned on its seat. 70

5. A heater of the character described comprising a heater casing having circulation openings through its top and spaced inlet and outlet openings and an interposed damper opening through its bottom, a radiating heater in the casing having an inlet 80 and an outlet end registering with said inlet and outlet openings and a radiating portion over said damper opening, a damper door, a segmental cam adapted to be oscillated for opening and closing the door, and means 85 operable from the top of the casing for oscillating the cam. 90

6. In a heater of the character described, the combination of a floor plate having ventilation openings, a heater-supporting housing beneath the floor plate and having a bottom air opening, a door for said opening, a cam-carrier having an arcuate inclined cam for opening said door, and a shaft to which said cam-carrier is fixed extending through 95 the floor plate and equipped thereabove with a hand lever for operating the cam-carrier. 100

7. A heater as set forth in claim 6, in which the inclined cam portion is adapted to be moved between and against a bearing 105 surface on the housing and on the door.

8. A heater as set forth in claim 6, including a compression spring on the shaft bearing against the housing for preventing vibration of the shaft with respect thereto. 110

9. A heater as set forth in claim 6, including means for limiting movement of the cam-carrier beyond a door closing and a full-open position.

10. A heater of the character described 115 comprising a floor plate having circulation openings and a marginal supporting flange shaped on its underside to provide a locating recess, a heater-supporting housing disposed beneath the floor plate and having a top 120 flange seated in said locating recess and adapted to overlie an edge of a floor board or the like for supporting the heater, and fastening means passing through the floor plate flange for clamping said floor plate 125 and the interposed housing flange to said floor board.
